UNITED STATES PATENT OFFICE

JOHN JOSEPH COOPER, OF LONDON, ENGLAND, ASSIGNOR TO UNDERWOOD ELLIOTT FISHER COMPANY, OF NEW YORK, N. Y., A CORPORATION OF DELAWARE

PAPER FEEDING AND RETAINING ARRANGEMENT FOR TYPEWRITERS

Application filed April 4, 1928, Serial No. 267,170, and in Great Britain July 15, 1927.

This invention relates to the simultaneous production of multiple copies of matter on a typewriter and has for its object to provide means for enabling one or more sheets of paper or the like to be inserted into and removed from a typewriter without disturbing the position of other sheets, and is particularly applicable to typewriters employed for the simultaneous production of invoices and day-book sheets.

According to the present invention the sheets so to be removed or inserted are narrower than the remaining sheets and means are provided for gripping the lateral margins of said remaining sheets approximately concurrently with the release of the usual feed rollers and vice-versa.

Preferably one or more of the feed rollers of a set or a part attached thereto is or are adapted to engage with one end of a double ended lever the other end of which is furnished with a gripping finger which, when said double ended lever is tilted by the rocking movement of the feed roller, is constrained towards the platen so as to grip the adjacent margin of the "remaining" sheet or sheets positioned on said platen.

One form of the invention will be described with reference to the accompanying drawings of which Figure 1 is a plan of a typewriter carriage wherein portions are omitted or are broken away for the sake of clearness; Figure 2 is a fragmentary plan to an enlarged scale, similar to Figure 1 but with the paper guide removed and indicated by broken lines; Figure 3 is a part sectional end elevation, the section being taken on the line 3-3 of Figure 2 showing the feed rollers in operative position; Figure 4 is a view similar to Figure 3 but with the feed rollers released and Figure 5 is a fragmentary sectional end elevation taken on the line 5-5 of Figure 2. Figure 6 is a sectional elevation, showing the rollers and gripper set to ineffective intermediate positions.

As shown in the drawings the platen or cylinder *a* of a typewriter is rotatably mounted in the ends *b b* of a carriage *c* which latter has fixed thereto a sloping paper rest *d* and carries a paper guide *e*.

The paper guide *e* is curved to conform with the surface of the platen *a* beneath which it extends, and is formed on its rear edge with tongues *f f*... which engage with slots *g g*... in the paper rest *d* so that the upper surfaces 55 of the rest *d* and guide *e* form a substantially continuous and unobstructed path for a sheet or sheets of paper or the like such as *h*.

The usual sets of front and rear feed rollers *j k* are adapted to be moved into and out of operative position by respectively raising and depressing the paper release lever *m* through the medium of a link *n*, lever *o*, cam *p* and rocking lever *q* all of which are of known construction with the exception of the rocking 65 lever *q* which is situated near the right hand end of the platen *a* and for the purposes of this invention is extended upwardly as at *r* so as to be adapted, when the paper release lever *m* is depressed, to extend through a slot 70 *s* in the guide *e* and press against the platen or against the paper *h*.

Near the left hand end of the platen *a* there is pivoted upon the usual feed roller supporting shaft or bar *t*, a double ended lever *u v*, 75 (see Figure 5), one end *u* of which extends beneath the rear feed roller spindle *w* whilst the other end *v* is upturned so that its tip, when the lever *u v* is tilted by the downward or release movement of the feed roller spindle 80 *w*, is constrained towards the platen *a* or the paper *h*, the paper guide *e* being cut away as at *x* to give passage to said end *v*. The spindle *w* is carried by the usual rock-arms, 85 extending from the shaft *t*.

In use, a large sheet or sheets of paper or the like *h* is or are inserted into the machine in the usual manner together with one or more narrower sheets the widths of which are less than the distance between the two gripping fingers *r* and *v*, the paper release lever *m* being in its raised position.

When it is desired to remove the smaller sheets without disturbing the remainder, the paper release lever *m* is depressed whereupon the feed rollers *j k* move on their usual arms away from the platen whilst the gripping fingers *r* and *v* are constrained to press against and grip the margins of the larger sheets. Thus, whilst the smaller sheets are 100

released so as to be capable of removal and substitution, the large sheets are retained in position.

For convenience in adjusting the positions of the whole of the sheets of paper or the like, both large and small it is convenient so to arrange the amplitude and relationship of the movements of the gripping fingers *r* and *v* and of the feed rollers *j* and *k*, that in the mid-positions of the respective movements of said fingers and rollers the whole of the sheets of paper or the like, will be released or gripped so lightly as to be capable of adjustment and it is convenient also to provide means for moving the paper release lever into an intermediate position and maintaining it therein so that whilst the feed rollers are substantially released, the gripping fingers are not yet in effective operation. For this purpose an auxiliary lever *y* may be mounted on that end of the carriage *c* adjacent to the paper release lever *m*, and be furnished with a transverse pin *z* adapted when the auxiliary lever *y* is rocked against the action of a light spring 11 to engage with a cam 12 formed on the adjacent edge of the paper release lever *m*. The positions, dimensions and shape of the auxiliary lever *y*, pin *z* and cam 12 are so arranged as to enable the paper release lever *m* readily to be moved into, and retained in, a suitable intermediate position by a simple rocking movement of the lever *y*.

By use of this invention a simple and inexpensive device is provided whereby the usual extraneous means for retaining sheets of paper or the like in position in a typewriter during the withdrawal and insertion of other sheets may be dispensed with and the operation be effected with accuracy and expedition.

The lever *u* with its gripping finger *v* is placed at the extreme left-hand end of the platen, Figure 2, and can co-operate with the adjacent U-shaped lever at this end of the platen (see Figure 4) to hold a wide sheet solely by means of the left-hand margin thereof, where said wide sheet fails to reach the right-hand gripper *r*. This gives a range of positions for the wide sheets at different stations lengthwise of the platen, so that the carbon-copies may be made in different zones or portions of the wide sheets, as desired; the narrow sheets feeding between the two grippers *r*, while the wide sheets may be held by the two grippers *r*, or by the three grippers *r* and *v*, or by the left-hand grippers *v*, *r* alone.

I claim:—

1. In a typewriter having a cylinder, feed rollers, a shaft, rocking arms pivoted to said shaft, a spindle for said feed rollers mounted on said arms, means operatively connected with said arms for rocking said feed rollers towards and away from said cylinder, a double ended lever pivoted to said shaft near one end thereof, one end of said double ended

lever lying in the path of said feed roller spindle and the other end having gripping means adapted, when said feed rollers are rocked away from said cylinder, to be constrained towards said cylinder. 70

2. In a typewriter having a cylinder, feed rollers, a feed roller release lever and means operatively connected with said feed roller release lever for gripping the lateral margins of sheets on said cylinder approximately 75 concurrently with the release of said feed rollers, means for moving said feed roller release lever to an intermediate position comprising an auxiliary lever, a transverse pin on said auxiliary lever and a cam on said feed roller release lever adapted to engage and coat with said transverse pin. 80

3. In a typewriting machine having a carriage and a cylinder with feed-rollers for feeding different widths of sheets around the cylinder, the combination of a lever for releasing said feed-rollers from a sheet-feeding position, sheet-clamping means controlled by said lever and operable to clamp the margin of the wider sheet to the cylinder, while one or more of the narrower sheets are inserted and removed from the cylinder, said clamping means arranged on the carriage near the end of the cylinder and adjacent to the feed-rollers, whereby the movement of said lever to release said rollers from their sheet-feeding position will move the clamp into a sheet-clamping position against the cylinder, and a finger-piece mounted on the carriage, having means to partially vibrate said lever to release the feed-rollers and not move the clamping means into a sheet-clamping position. 90 100

4. In a typewriting machine having a cylinder and feed-rollers, the combination with a feed-roller release key, of a gripper effective to grip the margin of a sheet on said cylinder by the casting off of said feed-rollers by said key, an independently-operable finger-piece, and means on said key and operable by said finger-piece for moving and maintaining said feed-rollers away from the platen, and moving said gripper towards the platen without gripping the sheet. 105
